UNITED STATES PATENT OFFICE.

WILLIAM MOORE, OF BREMERTON, WASHINGTON.

OIL-BURNER.

1,321,321.

Specification of Letters Patent. Patented Nov. 11, 1919.

Application filed October 1, 1918. Serial No. 256,467.

To all whom it may concern:

Be it known that I, WILLIAM MOORE, a citizen of the United States, and resident of Bremerton, county of Kitsap, and State of Washington, have invented certain new and useful Improvements in Oil - Burners, of which the following is a specification.

My invention relates to oil burners and particularly to that type which is intended for using fuel oils such as kerosene, gas oil, and the like, and also more particularly such as are intended for domestic use in stoves, whether heating or cooking stoves.

The object of my invention is to provide a burner for this kind of use which shall be simple in construction, durable, and easily kept in repair, and which will secure satisfactory heating results.

In the accompanying drawings I have shown my invention in a burner which is designed for insertion within the fire box of heating stoves. The manner in which the same would be modified for application to other stoves would be evident to any mechanician.

Figure 1 is a plan view showing one burner.

Fig. 2 is a sectional side elevation of the same device.

The base 1 of my device is a plate which, when the device is to be inserted within a fire pot of a stove, is made to fit the same. It is provided with a hole for each burner employed, through which air may pass freely to the burner. Such holes 10 are surrounded by upwardly extending flanges 11. Such flange 11 has two slots 12 placed diametrically opposite, in which is placed a pipe 2 which has a single discharge opening 20 located at the point 20, the said opening constituting the nozzle for the discharge of the gas which is generated from the oil supply.

One end of this pipe is closed, as by a cap 22. The other end is connected with a vertical section 21 which in turn connects with a coiled section 23, this latter being preferably in the form of a conical helix and constituting the regenerating or gasifying element. This latter coil section 23 is supplied through pipe 24 which in turn is connected with a pipe leading from any suitable source of supply whereby oil is delivered under sufficient pressure to cause it to flow to and through these pipes.

Lying within and supported by the coils of the section 23 of the pipe, is a frustum of

a hollow cone 3. As shown, this has curved sides, that is, more nearly resembling a frustum of a hyperbola. Within this is a smaller cone 4, which is supported away from the cone 3 by ribs 40 which, as herein shown, are secured to and form a part of the cone 4, although these ribs might as well be upon the outer cone 3. The purpose is to space apart the two cones so as to form an annular space through which supplemental air may be supplied to the point where ignition takes place. The two cones 3 and 4 are in alignment with the jet of gas discharged through the orifice 20.

Covering over both of the cones 3 and 4 is an ignition plate 5. This is supported slightly above the cones 3 and 4, and also the gas generating or regenerating pipes 23, by lugs or ribs 50, which are placed in radial position but which rest upon the pipe, and form in combination with cones 3 and 4 a combustion chamber having double walls with air ducts between to supply secondary air to the burning gases at the moment of ignition. For convenience the plate 5 is provided with an upwardly extending lug 51 by which it may be lifted when desired or necessary.

Between the lower ends of cones 3 and 4 and the pipe 2, in which is the nozzle 20, is placed a drip cup or saucer 6. This is in the nature of an annular trough which has a central hole 60. The flange 11 may have supporting arms 13 which engage the cup 6 to hold it properly placed. This cup may also rest upon the top of the pipe 2. The trough part of this cup is of such size and so placed that it lies immediately under the lower ends of both of the cones 3 and 4.

In starting the device oil may be discharged through the nozzle 20. This, if discharged with any force, will strike the plate 5, be caught by the conical tubes 3 and 4 and will, dripping downwardly, be caught by the cup 6. Here it will burn and heat the entire apparatus to the point where the oil will be gasified before being discharged.

The operation of this device is believed to be apparent. Upon sufficiently heating the pipes 23 the oil contained therein will become gasified and gas or oil will be discharged through the nozzle 20. This being discharged upward strikes the bottom of the cap plate 5 and is thrown outward. Ignition takes place beneath this cap plate.

At this point the supplemental air which

passes upward through the annular passage between the conical shells 3 and 4 is supplied and assists materially in the combustion. All parts of this device are capable of being removed if desired and necessary. They are also of such construction that they are cheap to manufacture and thus may be cheaply replaced if burned out or otherwise injured.

What I claim as my invention is:

- 10 1. In an oil burner, in combination, a base having a draft opening therein surrounded by an upwardly extending flange, said flange having two oppositely positioned pipe-receiving notches, a pipe fitting in said notches and having a discharge orifice in its upper side placed centrally of said opening and constituting a nozzle, a conical helix of pipe placed above said parts and connected with the nozzle pipe, and a deflecting plate supported from and spaced above the coiled parts of said pipe.
- 15 2. In an oil burner, in combination, a generator comprising a conically coiled pipe having an extension extending crosswise of and beneath said coil and provided with a discharge orifice forming a nozzle discharging centrally into said coil, a pair of nested and spaced apart conical shells supported within said pipe coils with their small end toward and alined with said nozzle, a priming cup placed between the nozzle and said conical shells to catch the oil drip from the shells and having a central opening through which the nozzle may discharge.
- 20 3. In an oil burner, in combination, a base having a draft opening therein surrounded by an upwardly extending flange, said flange having two oppositely positioned pipe-receiving notches, a pipe fitting in said notches and having a discharge orifice in its upper side placed centrally of said opening and constituting a nozzle, a conical helix of pipe placed above said parts and connected with the nozzle pipe, and a deflecting plate supported from and spaced above the coiled parts of said pipe.
- 25 4. In an oil burner, in combination, a generator comprising a pipe bent to form a conical helix and having an extension extending diametrically of and spaced away from the smaller end of the coils and also having a discharge orifice constituting a nozzle placed to discharge axially into said coils, a pair of nested conical shells, the outer one fitting within and supported by said coils, said shells having ribs spacing them apart to form auxiliary draft flues, and a cover plate having supporting lugs maintaining it spaced above and to cover said coils, and an annular trough-like drip cup placed between said shells and the nozzle with its central opening positioned to aline with the nozzle discharge, and a base having an opening surrounded with a flange, and means for positioning and supporting said pipe and the drip cup from said flange.
- 30 5. In an oil burner, in combination, a base having a draft opening therein surrounded by an upwardly extending flange, said flange having two oppositely positioned pipe-receiving notches, a pipe fitting in said notches and having a discharge orifice in its upper side placed centrally of said opening and constituting a nozzle, a conical helix of pipe placed above said parts and connected with the nozzle pipe, and a deflecting plate supported from and spaced above the coiled parts of said pipe.
- 35 6. In an oil burner, in combination, a base having a draft opening therein surrounded by an upwardly extending flange, said flange having two oppositely positioned pipe-receiving notches, a pipe fitting in said notches and having a discharge orifice in its upper side placed centrally of said opening and constituting a nozzle, a conical helix of pipe placed above said parts and connected with the nozzle pipe, and a deflecting plate supported from and spaced above the coiled parts of said pipe.

3. In an oil burner, in combination, a

generator comprising a conically coiled pipe having an extension extending crosswise of and beneath said coils and provided with a discharge orifice forming a nozzle discharging centrally into said coils, a pair of nested and spaced apart conical shells supported within said pipe coils with their small end toward and alined with said nozzle, a priming cup placed between the nozzle and said conical shells to catch the oil drip from the shells and having a central opening through which the nozzle may discharge.

4. In an oil burner, in combination, a generator comprising a pipe bent to form a conical helix and having an extension extending diametrically of and spaced away from the smaller end of the coils and also having a discharge orifice constituting a nozzle placed to discharge axially into said coils, a pair of nested conical shells, the outer one fitting within and supported by said coils, said shells having ribs spacing them apart to form auxiliary draft flues, and a cover plate having supporting lugs maintaining it spaced above and to cover said coils, and an annular trough-like drip cup placed between said shells and the nozzle with its central opening positioned to aline with the nozzle discharge, and a base having an opening surrounded with a flange, and means for positioning and supporting said pipe and the drip cup from said flange.

Signed at Seattle, Washington, this 10th day of September, 1918.

WILLIAM MOORE.
